UNITED STATES PATENT OFFICE.

MONROE KEETON, OF MERIDIAN, MISSISSIPPI.

FIRECRACKER HOLDER.

1,401,985.

Specification of Letters Patent. Patented Jan. 3, 1922.

Application filed February 24, 1921. Serial No. 447,581.

To all whom it may concern:

Be it known that I, MONROE KEETON, a citizen of the United States, and a resident of Meridian, in the county of Lauderdale and 5 State of Mississippi, have invented certain new and useful Improvements in Firecracker Holders, of which the following is a specification.

My present invention relates to holders for 10 fire crackers and aims to be an improvement over my former Patent No. 1,362,705.

The object of this invention is to produce 15 a device of extremely simple construction which will present no manufacturing difficulties and which will accomplish the desired object of my former patent, namely, to protect the hand of one exploding a fire cracker held in this device.

These and other objects I accomplish by 20 providing a handle which has mounted thereon a spring clamp adapted to pinch the fire cracker between itself and the handle. The end of the clamp may be bent backwardly to prevent sparks or fragments from 25 injuring the person holding the device.

The invention further consists in the novel construction, arrangement and combination of parts more fully hereinafter shown and described.

30 In the drawings, which are illustrative only—

Figure 1 is a side elevation of a preferred form of device.

Fig. 2 is a side elevation of a modification.

35 Fig. 3 is a perspective of the device of Fig. 2.

Referring now more particularly to the

drawings in which like numerals designate like parts throughout the several views, the invention consists of a handle, shown at 1, 40 of wood or any suitable material of any desired length, provided with a spring clamp 2 secured adjacent the upper end thereof. This clamp may be of any spring material 45 and is adapted to be fastened at its lower end as by screws 3, its other end normally engaging the flattened surface of the handle, as at 4. The upper portion of the handle may be recessed as at 5 to more securely position the fire cracker and prevent lateral 50 movement thereof.

The upper end of the clamp may be bent upwardly as shown in Fig. 2, which effectually serves as a shield to the person exploding the fire cracker.

It will be seen that the cracker may be slipped under the clamp of the device of Fig. 2, and pinched adjacent its fuse end, or under the bent portion of the clamp of Fig. 2, being held by its other end. In both 60 instances a portion of the clamp serves as a shield.

What I claim is:

A fire cracker holder comprising a handle having a flattened portion at one end thereof, a clamp secured to said handle and engaging the same by spring tension, said handle having a longitudinal recess, the spring tension portion of said clamp engaging the handle on each side of said recess and transversely thereof.

In testimony whereof I affix my signature.

MONROE KEETON.
